UNITED STATES PATENT OFFICE.

HECTOR LE DOUX, OF WORCESTER, MASSACHUSETTS, ASSIGNOR TO CROMPTON & KNOWLES LOOM WORKS, A CORPORATION OF MASSACHUSETTS.

LOOM.

933,187.

Specification of Letters Patent.

Patented Sept. 7, 1909.

Application filed July 5, 1907. Serial No. 382,147.

To all whom it may concern:

Be it known that I, HECTOR LE DOUX, a citizen of the United States, residing at Worcester, in the county of Worcester and 5 State of Massachusetts, have invented certain new and useful Improvements in Looms, of which the following is a specification.

My invention relates to looms, and more particularly to an attachment for a loom 10 used for making weft or chenille, as a material to be woven into rugs.

In manufacturing weft or chenille to be woven into rugs, there is ordinarily a filling of coarse woolen yarn thrown into a shed 15 composed of fine and strong warp threads, which are preferably used in small numbers in separate sections, at regular distances from each other. These warp threads are for the purpose of binding the filling and 20 holding it, so that when the woven fabric is cut into strips, the woolen yarn filling is held firmly.

In the weft or chenille to be woven into rugs, as ordinarily made, the warp threads 25 are woven around the coarse woolen filling in the form of a doup, and doup heddles are employed to produce the woven fabric, which is afterward cut into strips, but a single doup does not bind and hold the fill- 30 ing as it should be bound and held, and consequently the weft or chenille is liable to be torn or drawn apart, after the woven fabric has been cut into strips.

The object of my invention is to provide 35 an attachment for looms of the class referred to, in which a series of needles, arranged in pairs are used, a pair of needles for each section of warp threads, and each needle of a pair is mounted independently, and the 40 two needles have a simultaneous pivotal or rocking motion toward and from each other at their threaded ends. Each needle carries a thread and the two threads, through the movement of the needles, form a binding for 45 the warp threads. In case for instance four main warp threads are used, there are two additional threads used with the two needles to obtain two separate selvages, one on each side of the four warp threads.

50 I have only shown in the drawings a detached portion of a loom with my improvements combined therewith, sufficient to enable those skilled in the art to understand the construction and operation thereof.

55 Referring to the drawings:—Figure 1 is a

vertical cross section through the loom arch, the lay, and two harnesses, and my improvements combined therewith, looking in the direction of arrow *a*, Fig. 3, and showing the lay in its rear position. Fig. 2 corresponds 60 to Fig. 1, but shows the lay in its forward position. Fig. 3 is a section, on line 3, 3, Fig. 2, looking in the direction of arrow *b*, same figure, showing a rear view of the lay; the harnesses are not shown in this figure. 65 Fig. 4 shows a part of the needle motion shown in Fig. 3, detached; the needles are in a different position. Fig. 5 is a section, on line 5, 5, Fig. 4, looking in the direction of arrow *c*, same figure. Fig. 6 shows, on an 70 enlarged scale, a detached section of the woven fabric. Figs. 7, 8, 9, and 10 are dia-grammatic views, showing the method of weaving with my improvements.

In the accompanying drawings, 1 is a portion 75 of the lay beam, 2 the reed, 3 the hand rail, 4, Fig. 3, the upper portion of the lay sword, 5 and 6 two vertically moving harnesses which form the shed, in the usual way, and are operated by cam levers, not 80 shown, and have the upper strap 7 passing over a harness roll 8 on the harness roll shaft 9 mounted in brackets 10 secured to the loom arch 10'.

All of the above mentioned parts may be 85 of the usual and well known construction.

I will now describe my improvements.

On the upper side of the hand rail 3, at 90 each end thereof, (only one end is shown in the drawings,) is secured a stand 11, having in this instance a vertically extending undercut groove therein, forming a track or guide-way for a vertically moving plate or rail 12, which has an angle-shaped end 12' which engages the groove in the stand 11. 95 The rail 12 has on its rear side, at each end thereof, two lugs or ears 12'' to receive a pin 13, on which is pivotally mounted the hub 14' on the lower end of a connector 14. The upper end of the connector 14 has a hub 14'' thereon, which is pivotally mounted on a pin 15, which is adjustably secured by a nut 15' in an elongated opening 16' in the end of a stationary arm 16, which in this instance is bolted or secured to the rear end 100 of the loom arch, see Fig. 2. As the lay beam 1 moves backward from the position shown in Fig. 2, to the position shown in Fig. 1, the rail 12, through the connector 14, is moved downwardly on the stand 11. It 105 110

will be understood that a second arm 16 and connector 14, are located at the opposite end of the loom, not shown.

The vertically moving rail or plate 12 has thereon, at regular distances apart, and extending in a horizontal line upon the rear side of the plate 12, a series of studs or pins 17. Each stud or pin 17 has loosely mounted thereon two blocks 18, and 19, one of said blocks, as 18, receives and holds the upper end of a needle 20, and the other block, as 19, receives and holds the upper end of a needle 21. The lower ends of the needles 20 and 21 have openings or eyes 20' and 21', respectively, through which pass the threads 22, and 23, respectively, from a separate beam, not shown. Each block 18 has a pin 18' thereon, and each block 19 has a pin 19' thereon, said pins 18' and 19' are preferably on opposite ends of the blocks. The pins 18' are adapted to extend into openings or slots 24' in the lower edge of a second rail or plate 24, and the pins 19' are adapted to extend into openings or slots 24'' in the upper edge of said rail or plate 24. The rail or plate 24 is in this instance movably held in place, relative to the rail or plate 12, by screws 25, which extend through elongated openings 24''' in the rail or plate 24, at each end of said rail or plate; only one end of said plate is shown. The plate 24 is adapted to have a vertical movement with the plate 12, and also a longitudinal reciprocating movement relative to the plate 12, and by means of said movement each pair of needles 20, and 21, carrying the threads 22 and 23, are moved or rocked in opposite directions, simultaneously, and caused to move toward each other and away from each other at their threaded ends.

The rail or plate 24 has a reciprocating movement communicated thereto, in this instance through a cam lever or arm 26, having its hub 26' loosely mounted on a stud 27 on the arm 16; the cam lever 26 extends above the harness roll shaft 9 in this instance, and is adapted to be engaged by the cam-shaped surface 29' on a roll 29, fast on the harness roll shaft 9, and to have a reciprocating rocking movement communicated thereto, through the rocking of said shaft 9 by the raising and lowering of the harnesses 5 and 6. The cam lever 26 carries a pin 26'' at its outer end, on which is pivotally mounted the hub 30' of a connector 30; the lower end of the connector 30 has a hub 30'' thereon, which is pivotally connected with one arm 31' of an angle lever 31; the hub 31'' of which is pivotally mounted on a stud 32 on an upper extension 12^a on the end of the rail or plate 12. The other arm 31''' of the angle lever 31 has its end forked, to extend over a rounded or rod-shaped extension 24^a on the longitudinally moving rail or plate 24. A helically coiled expansion spring 33

encircles said rod extension 24^a and bears at one end against a pin 33' on said rod 24^a, and at its other end against the forked end on the angle lever arm 31''. The spring 33 forms a yielding connection intermediate 70 the angle lever 31 and the plate or rail 24, to allow the lever 31 to have more motion than is required to move the plate or rail 24. A second helically coiled expansion spring 34 encircles a second rod-shaped extension 75 24^b, on the end of the rail or plate 24, and bears at one end against the end of said plate, and at its other end against two lugs or ears 12^a' on the end of the plate 12. The helically coiled expansion spring 34 acts to 80 move the rail or plate 24 in a direction opposite to the direction of movement caused by the angle lever 31. An adjusting screw 35 turns in a threaded opening in an ear 12^b' on the plate 12, and is adapted to engage at 85 its inner end the outer end of the rod extension 24^b on the plate 24, to limit the movement of said plate in one direction, see Fig. 3.

Between each pair of needles 20 and 21, and the reed 2, is a downwardly extending 90 plate or strip 36, which is secured to the plate or rail 12, and extends downwardly therefrom to separate each pair of main warp threads 37 at the rear of the reed 2, so as to have a larger space between them 95 to insure the entering of the needles 20 and 21 between said warp threads, on the downward movement of said needles.

From the above description in connection with the drawings, the operation of my improvements will be readily understood by those skilled in the art. When the lay is in its rear position, see Figs. 1, and 7, the vertically moving rail 12 will be in its lowest position, and each pair of needles 20 105 and 21 will be in their lowest position, to carry the binding threads 22 and 23 below the lower plane of the main warp threads 37. The shuttle, not shown, with the coarse woolen yarn filling 38, is now thrown through 110 the shed, and on the forward movement of the lay to its extreme forward position, see Figs. 2 and 8, the vertically moving rail 12 through connector 14, is raised, and with it the needles 20 and 21. At the same time 115 the harnesses 5 and 6 change the shed, and the harness roll shaft 9 will be partially rotated, and also the cam collar 28^a. The rotation of the cam roll 29 having the cam surface 29' thereon, will raise the lever 26, 120 supposing it to be in its lowered position, and through connector 30, rock the angle lever 31, and through said angle lever 31 and the spring 33 move the rail or plate 24 to the left, and through the movement of 125 said plate 24 move the needles 20 and 21, which are above the upper plane of the main warp threads 37, as shown in Figs. 2 and 8, to the other side of a vertical line. On the backward movement of the lay, see Figs. 1, 130

and 9, the vertically moving rail 12 is moved downwardly, and with it the needles 20 and 21, to carry the binding warps 22 and 23 on the other side of the general main warp threads 37. The shuttle will now be thrown through the shed with the coarse woolen yarn filling 38. On the forward movement of the lay, see Figs. 2, and 10, the needles 20 and 21 will be moved into their opposite position again, and the operation will be repeated as the loom continues to operate, and the fabric will be woven, as shown in Fig. 6, as will be well understood by those skilled in the art.

15 It will be understood that the details of construction of my improvements may be varied if desired, and they may be adapted for weaving fabrics of different kinds.

Having thus described my invention, what 20 I claim as new and desire to secure by Letters Patent is:—

1. In a loom of the class described, a lay, a series of needles carried on and movable with the lay, and arranged in pairs, one pair 25 of needles for each section of warp threads, and each needle carrying a binding thread, and the two needles of each pair mounted independently of each other and adapted to have a pivotal or rocking motion, and means 30 for moving said needles in a vertical plane, and means for giving a pivotal or rocking motion to all of the series of needles simultaneously.

2. In a loom of the class described, a lay, 35 a series of needles carried on and movable with the lay, and arranged in pairs, one pair of needles for each section of warp threads, and each needle carrying a binding thread and the two needles of each pair 40 mounted independently of each other, and adapted to have a pivotal or rocking motion toward and away from each other, and means for moving said needles in a vertical plane, and means for giving a pivotal or 45 rocking motion to all of the series of needles simultaneously, through a single connection to operating mechanism.

3. In an attachment for a loom of the class described, a series of needles arranged 50 in pairs, one pair of needles for each section of warp threads, and each needle carrying a

binding thread, and the two needles of each pair mounted independently of each other, and adapted to have a pivotal or rocking motion toward and away from each other, 55 and means for raising and lowering said needles, and means for moving them in opposite directions, said last named means including a reciprocating rail or plate, carried on and movable with the rail or plate 60 carrying the needles.

4. In an attachment for a loom of the class described, a series of needles arranged in pairs, one pair of needles for each section of warp threads, and each needle carrying a 65 binding thread, and the two needles of a pair mounted independently of each other, and adapted to have a pivotal or rocking movement, and means for operating said needles to form a binding for the warp 70 threads, said means comprising a vertically moving plate on which said needles are supported, and a second longitudinally moving plate, and means for moving said longitudinally moving plate at regular intervals, to 75 cause the movement of the needles toward and away from each other.

5. In a loom of the class described, a lay, needles carried on and movable with the lay, and means for communicating a pivotal or 80 rocking movement to the needles, said means comprising a reciprocating rocking roll having a cam surface thereon, and connections to the harness mechanism for rocking said roll, a cam lever, and connections intermediate 85 said lever and the needles.

6. In a needle motion attachment for a loom, a needle or needles, means for communicating a pivotal or rocking movement to the needle or needles, comprising a harness roll shaft adapted to have a reciprocating rocking movement, a roll fast on said shaft and having a cam surface thereon, a cam lever, a connector from said cam lever to an angle lever, and said angle lever, and 95 connections intermediate said angle lever and the needle or needles.

HECTOR LE DOUX.
